US0D1046665S

(12) **United States Design Patent** (10) Patent No.: **US D1,046,665 S**
(45) Date of Patent: ** Oct. 15, 2024

(54) **SENSOR TRANSMITTER FOR MEASURING AIR PRESSURE OF A TIRE**

(71) Applicant: **PACIFIC INDUSTRIAL CO., LTD.**,
Ogaki (JP)

(72) Inventors: **Takumi Sugino**, Ogaki (JP); **Shoji Mizutani**, Mizuho (JP)

(73) Assignee: **PACIFIC INDUSTRIAL CO., LTD.**,
Ogaki (JP)

(**) Term: **15 Years**

(21) Appl. No.: **35/516,662**

(22) Filed: **Mar. 24, 2022**

(80) **Hague Agreement Data**

Int. Filing Date: **Mar. 24, 2022**

Int. Reg. No.: **DM/219811**

Int. Reg. Date: **Mar. 24, 2022**

Int. Reg. Pub. Date: **Mar. 24, 2023**

(51) **LOC (14) Cl.** **10-04**

(52) **U.S. Cl.**

USPC **D10/85**; D10/86

(58) **Field of Classification Search**

USPC D10/75-86, 96-103, 104.1, 104.2

CPC B60C 29/005; B60C 29/002; B60C 29/06;
B60C 23/0408; B60C 23/0494; B60C
23/041; Y02E 60/10

See application file for complete search history.

LLP

(57) **CLAIM**

The ornamental design for a sensor transmitter for measuring air pressure of a tire as shown and described.

DESCRIPTION

1.1 : Perspective

1.2 : Perspective

1.3 : Front

1.4 : Back

1.5 : Top

1.6 : Right

1.7 : Left

1.8 : Bottom

1.9 : Partial enlarged view

1.10 : Partial enlarged view

(Continued)

The broken lines in the drawings form no part of the claimed design; shading lines on the surface do not form part of the claimed design; the present article is made of resin.
